UNITED STATES PATENT OFFICE.

HERMAN CARL SCHMIDT, OF NEW YORK, N. Y.

WATER-TOWER.

SPECIFICATION forming part of Letters Patent No. 602,244, dated April 12, 1898.

Application filed April 16, 1897. Serial No. 632,394. (No model.)

To all whom it may concern:

Be it known that I, HERMAN CARL SCHMIDT, of the city, county, and State of New York, have invented certain new and useful Improvements in Water-Towers, of which the following is a specification.

My invention relates to that class of water-towers in which an extensible discharge-pipe mounted upon a suitable truck is raised from a horizontal position to a vertical position, so that a stream of water may be directed into the upper parts of buildings in cases of fire; and my improvements are directed particularly to the mechanism for raising, lowering, and extending said discharge-pipe and for controlling and directing the stream of water discharged therefrom, details of all of which are hereinafter more fully set forth.

In the drawings, Figure 1 is a side elevation of my improved water-tower with the discharge-pipe lowered. Fig. 2 is a view of the forward end of the truck in the same position with the tower raised. Fig. 3 is a similar view with the tower turned at right angles to the position shown in Fig. 2, with the rear of the tower toward the observer. Fig. 4 is a plan view of the truck, the tower being raised and shown in section on the lines $x-x$ of Fig. 2; Fig. 5, a view of the nozzle and braces, taken at right angles to Fig. 2, looking from the left. Fig. 6 is a cross-sectional view of the tower, taken on the lines $y-y$ of Fig. 2. Fig. 7 is a detail of the locking mechanism for the side braces. Fig. 8 is a longitudinal partly-sectional view of the upper part of the turn-table, the lowering cable, and connections. Fig. 9 is a top view of a pawl attached to a section of frame, showing the cam-lug on the pawl. Fig. 10 is a cross-sectional view of the same; and Fig. 11 is a front view of the brake-lever and connections, with the lever lowered.

Corresponding parts are designated by the same reference-letters in all the figures.

45 A is the truck-frame, which is mounted upon running-gears in the usual manner. At the forward end of this frame is mounted the turn-table B B', which carries the tower and its attachments.

50 C C are brackets bolted to the top B' of the turn-table, braced by suitable stay-rods c c, the rear extensions of these brackets support-

ing the hoisting-windlass and attachments, and the forward ends being provided with bearings c' c', in which are journaled the arms 55 of a cross-frame d, to which is attached the main tower-standard D, which is laterally braced by guy-rods d' d'.

At the top of the standard D is mounted a frame E, consisting of an upper member E' 60 and a lower member E'', connected by bars e e' e' e'', forming between them the slotted ways e'.

The brackets C C have along their bases the slotted tracks c' c'', in which travel the 65 ends of a transverse shaft F, said ends being provided with suitable antifriction-rollers f f. This shaft F carries the feet g g of the trussed tower-brace G, the upper ends of which are connected by a rod g', provided with antifriction-rollers g' g'', which travel in the slotted ways e' e'' of the frame E. Links H H are pivoted to the sides of the brace G at h h and to the arms of the cross-frame d.

70 I is a transverse shaft mounted in the brackets C C, (see Fig. 4,) having angular ends i i to be grasped by the socketed heads of suitable crank-handles and being provided with a gear-wheel i', meshing with a larger gear-wheel j upon the windlass-shaft J. This shaft 75 J has upon its other end a ratchet-wheel j', controlled by a pawl j'' upon the bracket C, and it is also provided with conical grooved drums J J' near either end and with a similar intermediate drum J'.

75 j' j'' are eyeleted collars attached to the shaft and may be secured thereto through an intermediate pawl and ratchet to permit of their being adjusted to take up any slack in the hoisting-cable K, which, starting from one of the collars j' j'', is carried to and over a sheave f' on the shaft F, then around the sheaves l l on the cross-bar L, and then is attached to the second collar j'. A second cable K' (shown by dotted lines in Fig. 4) is fastened at one 80 end to the shaft J in a position to be wound upon the drum J', from which it is carried to and around the sheave c' at the front of the turn-table, then back and around the sheave f' upon the shaft F, and then attached to the 85 sheave-holder c'' by being passed through the hollow shank c'. The sheave c' is mounted in a forked arm c'', the extension c' of which is flattened laterally to prevent rotation,

threaded, and slides through the bracket c^7 and is adjusted by lock-nuts C^6 C^6 , by means of which the tension may be regulated. Phosphor-bronze cables are best adapted for this use, as they preserve their tension and are not injured by water.

A block m slides upon the standard D , but is prevented by the fin d^2 (see Fig. 4) from swinging around it. This block at its other end carries the extensible pipe M , which passes up between the grooved guide-rollers e^3 e^3 in the top frame E . On the upper end of the pipe M is a section of flexible hose M' , which extends to the nozzle M^2 . The hose M' is supported laterally by the arms m' m' , to which are pivoted the links m^2 m^2 , the upper ends of which are pivoted to the base of the nozzle, from the front of which depends the T -brace m^3 , the cross-bar of which by engaging with the links m^2 m^2 and the hose M' limits the swing of the nozzle between the links m^2 m^2 . As is well understood, when a stream of water is passing through the pipe its pressure will tend to throw the nozzle into a vertical position; but through the cord n , attached to the nozzle and led down through the eyeleted guy-rod m^4 to the windlass N , the nozzle may be bent forward to any desired angle, while by the knot n' , encountering the guy-rod m^4 , the nozzle is prevented from flying over backward.

From the block m a cable O travels up over a sheave D' at the top of the standard D and then down to a windlass P , carried by extensions of the frame d and which is driven, by means of the cranks $p p$, upon the shaft p' , carrying the gear-wheel p^2 , meshing with the gear-wheel p^3 upon the windlass-shaft. A pawl p^4 controls a ratchet-wheel upon the shaft p' to prevent the unwinding of the cable except when desired. From the pipe M a hose Q is led back over guide-rollers R R' (additional guide-rollers may be inserted, if desired) and is connected with the discharge-pipes of the air-chamber S , which is mounted in the body of the truck and which is provided with the usual inlets s s' s' and which is also connected by a discharge-pipe t with the swiveled nozzle T .

At either side of the truck-frame are mounted braces U U , which are pivoted in blocks u u , hinged in brackets u' u' upon the frame A . The lower extensions of these brackets u' u' are split or forked, and when the braces U U are swung out at right angles, or nearly so, to the frame they fall between the forks until their lower ends reach the ground. In this position they are firmly locked by means of the hand-screws V V , threaded through the outer ends of the blocks u , so that a rigid brace is provided on each side of the truck, which is of great importance when the tower is in operation. The effectiveness of these braces is increased by providing the lower ends with claws u^2 , which prevent the ends from slipping upon the pavement. When not in use, the braces U U are swung up into car-

rying-hooks W W , in which position they may also be locked, if desired, by means of the hand-screws V V .

At either side of the truck are placed rollers A' A' for the hose to render over when the tower is revolved on its turn-table, and as in case of a half-revolution the rear ends of the brackets would encounter the brake-lever B^2 , I hinge the brake-lever at b and secure the sections together by a set-screw b' , by loosening which the front end of the lever will be permitted to drop down, as shown by the dotted lines in Figs. 3 and 11.

In order to readily hold the various detents in their positions out of engagement, I prefer to make them with projecting cam-lugs, as shown at j^5 , Figs. 9 and 10, which by jamming against the adjacent frame when the detents are raised and thrown over backward will hold the detents out of engagement until they are again thrown over and down by hand.

The operation of my invention is as follows: The tower, being lowered, is drawn upon the truck to the desired position. The braces U U are unhooked from the supports W W and swung out and set in the position shown in Figs. 2, 3, and 4 to brace the truck laterally. Crank-handles are then slipped upon the ends of the shaft I , and the shaft I is revolved, and through the gears i' j' it revolves the windlass J , winding the cable K upon the conical spiral drums J' J' , and thereby drawing the shaft F and the foot of the tower-brace G back toward the windlass, the roller-borne ends of the shaft F traveling in the slotted ways C^2 C^2 ; but the tower-brace G , being linked to the frame d by the links H H , is, by the movement already described, swung upon the link-pivots, and its outer end or top is gradually thrown up, carrying with it the main standard D and its attachments, the rollers g^2 g^2 traveling downward in the slotted ways as the brace and standard are raised. This movement is continued until the standard has been raised to a vertical position, the cross-rod g' passing down past the spring-dog e^4 , which then flies forward and hooks over the rod, thus locking the brace and standard together. At the same time the ends of the shaft F pass back under the hooked detents f^5 f^5 , which then drop down, hooking the foot of the brace securely in position. It will be seen that the greatest resistance is encountered at the first movement in raising the brace G , and at this point by having the cable K wound about the smallest part of the conical drums J' J' , I secure the greatest power, the resistance being equalized as the hoisting proceeds by winding the cable gradually about the greater diameter of the drums, which also increases the speed with which the brace rises. The same rotation which winds the cable K upon the drums J' J' unwinds the cable K' from the drum J^2 , permitting the drawing back of the shaft F , as described.

By the arrangement described I am en-

abled to apply the raising power at the end of the standard D, which is thus pushed and lifted, without subjecting its base or other portions to any such strain or force as must exist when the lifting power is applied near the pivotal point of the standard. This saves wear and tear in the operation of the tower and increases the safety and facility of its use. By turning the crank-handles p p and

the shaft p' and gears p^2 and p^3 the windlass P is revolved, winding up the cable O and drawing up the discharge-pipe M and its nozzle M^2 to the desired height. The stream of water may be now turned into the air-chamber S and from thence discharged through the hose Q, pipe M, and nozzle M^2 .

In water-towers of this general class there is a considerable tendency to vibration, owing to the height of the structure, the narrowness of its supporting-base, the weight of the structure itself and of the moving stream of water, and this vibration is materially increased by the motion of the stream and the pulsations produced in the stream by the pumping of the engines. To reduce pulsation and lessen the consequent vibration of the tower, I make use of the air-chamber S, into which the streams from the engines are directed and by means of which the pressure

is equalized, so that the stream will be discharged into the hose Q with a steady even flow and the trembling or vibrating of the tower will be in a large measure avoided. The vertical angle at which the stream is dis-

charged may be regulated by means of the cord n, which can be wound or unwound upon the windlass N, and the lateral angle of the stream is regulated by turning the tower upon its table by means of socketed capstan-bars slipped over the pins b^2 b^3 (see Fig. 4) upon the upper member B' of the turn-table. A lock-pin B³ passes through both members of the turn-table and prevents rotation until the pin is removed.

To lower the tower, the water is first shut off. The pipe M is then lowered, the hose being drawn back and looped upon the floor of the truck. The detents f^5 f^6 are then raised, freeing the ends of the shaft F. The dog e⁴ is then pulled back off the rod g' by means of the hand-line g⁶. The tower-brace is now un-

locked. The pawl j³ is freed from the ratchet-wheel j², and by reversing the windlass J the cable K' will be rewound upon the drum J², pulling the foot of the brace forward and causing the brace to descend into its folded position. At the same time the cable K is paid off of the drums J' J', so as to permit the described movement of the tower-brace.

In this way the tower is lowered into its horizontal position. The braces U U are then unlocked and swung into their supporting-hooks, and the tower and truck are ready for removal.

Having thus described my invention, what I claim, and desire to secure by Letters Patent of the United States, is—

1. In a water-tower, the combination of a base-frame, a main standard pivoted therein, a tower-brace having its top in contact with said main standard and its foot in sliding connection with said base-frame, intermediate link connections between the tower-brace and the base-frame, a cable for hoisting said tower-brace and a cable for lowering the same, substantially as described. 70

2. In a water-tower, the combination of a base-frame, a main standard pivoted therein, a tower-brace having its top in sliding contact with said main standard and its foot in sliding connection with said base-frame, intermediate link connections between the tower-brace and the base-frame, a cable for hoisting said tower-brace and a cable for lowering the same, substantially as described. 80

3. In a water-tower, the combination of a base-frame, a main standard pivoted therein, a tower-brace having its top in contact with said main standard and its foot in sliding connection with said base-frame, intermediate link connections between the tower-brace and the base-frame, a windlass-shaft provided with a hoisting-drum and a lowering-drum, a cable for hoisting said tower-brace and cable for lowering the same, substantially as described. 90

4. In a water-tower, the combination of a base-frame, a main standard pivoted therein, a tower-brace having its top in contact with said main standard and its foot in sliding connection with said base-frame, intermediate link connections between the tower-brace and the base-frame, a windlass-shaft provided with a pair of conical, spirally-grooved hoisting-drums, and a similar lowering-drum with relatively-reversed groove, a cable for hoisting said tower-brace and a cable for lowering the same, substantially as described. 100

5. In a water-tower, the combination of a base-frame, a main standard pivoted therein, a tower-brace having its top in contact with said main standard and its foot in sliding connection with said base-frame, intermediate link connections between the tower-brace and the base-frame, a cable for hoisting said tower-brace and a cable for lowering the same, both of said cables operating upon the foot of the tower-brace, substantially as described. 110

6. In a water-tower, the combination of a base-frame, a main standard pivoted therein, a tower-brace having its top in contact with said main standard and its foot in sliding connection with said base-frame, intermediate link connections between the tower-brace and the base-frame, a windlass-shaft provided with a pair of conical spirally-grooved hoisting-drums, and a similar lowering-drum with relatively-reversed groove, a cable for hoisting said tower-brace and a cable for lowering the same, both of said cables operating upon the foot of the tower-brace, substantially as described. 120

7. In a water-tower, the combination of a base-frame, a main standard pivoted therein,

a tower-brace having its top in sliding contact with said main standard and its foot in sliding connection with said base-frame, a cable for hoisting said tower-brace and a cable for lowering the same, substantially as described.

8. In a water-tower, the combination of a base-frame provided with slotted tracks, a main standard pivoted therein, a tower-brace having its top in sliding contact with said main standard and its foot mounted upon a transverse shaft, provided with antifriction-rollers traveling in the slotted tracks of said base-frame and held thereby in sliding connection with said base-frame, a cable for hoisting said tower-brace and a cable for lowering the same, substantially as described.

9. In a water-tower, the combination of a base-frame, a main standard pivoted therein, a tower-brace having its top in contact with said main standard and its foot in sliding connection with said base-frame, hoisting-cable sheaves traveling with the foot of said tower-brace, a lowering-cable, a windlass-shaft provided with two hoisting-drums and a lowering-drum, a hoisting-cable traveling over said hoisting-cable sheaves and having one end attached to each of said hoisting-drums, and a lowering-cable traveling over said lowering-cable sheaves and having one end attached to said lowering-drum, substantially as described.

10. In a water-tower, the combination of a base-frame, a main standard pivoted therein, a tower-brace having its top in contact with said main standard and its foot in sliding contact with said base-frame, hoisting-cable sheaves traveling with the foot of said tower-brace, intermediate hoisting-cable sheaves, a lowering-cable sheave attached to said base-frame, an intermediate lowering-cable sheave, a windlass-shaft provided with two hoisting-drums and a lowering-drum, a hoisting-cable traveling over said hoisting-cable sheaves and having one end attached to each of said hoisting-drums, and a lowering-cable traveling over said lowering-cable sheaves and having one end attached to said lowering-drum, substantially as described.

11. In a water-tower, the combination of a base-frame, a main standard pivoted therein, a tower-brace having its top in sliding contact with said main standard and its foot in sliding connection with said base-frame, a detent to lock the top of said tower-brace to said main standard, and a detent to lock the foot of said tower-brace to said base-frame, said detents operating when the main standard has been brought into an elevated position, substantially as described.

12. In a water-tower, the combination of a base-frame, a main standard pivoted therein, a tower-brace having its top in contact with said main standard and its foot in sliding connection with said base-frame, and a detent to lock the foot of said tower-brace to said base-frame, said detent operating when the main

standard has been brought into an elevated position, substantially as described.

13. The combination, with the tower raising and lowering mechanism of a water-tower, of a windlass-shaft provided with both a hoisting-cable drum and a lowering-cable drum, a hoisting-cable sheave and lowering-cable sheave carried upon a common shaft, a hoisting-cable winding upon said hoisting-cable drum and traveling over said hoisting-cable sheave, and a lowering-cable winding reversely upon said lowering-cable drum and traveling over said lowering-cable sheave, whereby reverse movements are communicated to said common shaft by reversing the revolutions of said windlass-shaft, substantially as described.

14. The combination, with the tower raising and lowering mechanism of a water-tower, of a windlass-shaft provided with both a hoisting-cable drum and a lowering-cable drum, a hoisting-cable sheave and lowering-cable sheave carried loosely upon a common shaft, a hoisting-cable winding upon said hoisting-cable drum and traveling over said hoisting-cable sheave, and a lowering-cable winding reversely upon said lowering-cable drum and traveling over said lowering-cable sheave, whereby reverse lateral movements are communicated to said common shaft by reversing the revolutions of said windlass-shaft, substantially as described.

15. The combination, with the tower raising and lowering mechanism of a water-tower, of a windlass-shaft provided with both a hoisting-cable drum and a lowering-cable drum, a hoisting-cable sheave and lowering-cable sheave carried upon a common shaft, a hoisting-cable winding upon said hoisting-cable drum and traveling over said hoisting-cable sheave, and a lowering-cable winding reversely upon said lowering-cable drum and traveling over said lowering-cable sheave, whereby reverse movements are communicated to said common shaft by reversing the revolutions of said windlass-shaft, and an intermediate adjustable sheave for regulating the tension in said cables, substantially as described.

16. A water-tower adapted to be brought into an erect position, a cable for drawing the tower into such position, a cable for lowering the tower, an adjustable sheave over which the lowering-cable runs, said sheave being provided with a hollow, exteriorly-threaded shank within which one end of the lowering-cable is secured, and which shank is provided exteriorly with lock-nuts for adjusting said sheave and thereby regulating the tension in said cable, substantially as described.

17. A water-tower adapted to be brought into an erect position, a cable for drawing the tower into such position, a cable for lowering the tower, an adjustable sheave carrying said lowering-cable, said sheave being

provided with a hollow, exteriorly-threaded shank within which one end of the lowering-cable is secured, a guide-block through which said shank extends, lock-nuts for adjusting 5 said shank and thereby regulating the tension of said cable, and a windlass, provided with a plurality of conical, spirally-grooved drums, for operating said cables, substantially as described.

45

21. In a water-tower, the combination with the running-gears and frame of a truck, of a supporting-table mounted thereupon, a base-frame provided with slotted tracks carried by said table, a main standard having its 50

foot pivoted in said base-frame, a tower-brace, having its top in sliding contact with

said main standard, and carried upon a transverse shaft provided with antifriction-rollers traveling in said slotted tracks of said 55

base-frame, and also provided with two hoisting-cable sheaves and a centrally-disposed

lowering-cable sheave, a pair of arms linking the tower-brace to said base-frame above 60

said slotted tracks, a pair of intermediate

hoisting-cable sheaves carried by said base-frame, a windlass-shaft provided with a conical, spirally-grooved drum upon each end, a 65

cable passing around all of said hoisting-cable sheaves and having one of its ends se-

cured to each of said drums, a third conical drum, with relatively-reversed spiral grooves, 70

mounted centrally upon said windlass-shaft, an adjustable lowering-cable sheave mounted

upon said base-frame, a lowering-cable, hav- 75

ing one end secured to said last-mentioned

drum and the other end to the shank of said

adjustable sheave, and passing around the

said adjustable sheave, and said centrally- 80

disposed lowering-cable sheave, substantially

as described.

85

18. In a water-tower, the combination, with the running-gears and frame of a truck, of a 90

tower-supporting frame, a main standard having its base secured in said frame, and provided at its opposite end with slotted

guideways, a tower-brace supported in said frame and in sliding connection therewith, 95

its upper end engaging in the slotted guide-ways, aforesaid, and means for sliding out

the foot of the brace and thereby erecting 100

the standard, substantially as described.

19. The combination, in a water-tower, of a 105

main standard, provided with a vertical fin and with a head-block carrying two hour-

glass guide-rollers, a discharge-pipe passing 110

between said guide-rollers, a base-block, for supporting the end of said discharge-pipe

sliding upon said standard and provided with a recess corresponding to said fin, a cable at-

tached to said block and traveling over a 115

sheave mounted upon said standard, and a

windlass for operating said cable and there- 120

by raising and lowering said pipe, substan-

tially as described.

20. The combination, with the outlet of 125

the discharge-pipe of a water-tower, of a sec-

tion of hose extending to the nozzle, a pair 130

of arms projecting beyond the end of said

discharge-pipe, a pair of pivoted links ex- 135

tending from said arms to the base of the

nozzle and pivoted thereto preventing lat- 140

erally bending of the nozzle, a T-stop depend-

ing from the nozzle-base and its cross-bar en-

gaging said links and hose, and a nozzle-line

for depressing said nozzle, substantially as

described.

145

21. In a water-tower, the combination with the running-gears and frame of a truck, of a 150

tower-supporting frame, a main standard having its base secured in said frame, and provided at its opposite end with slotted

guideways, a tower-brace supported in said frame and in sliding connection therewith, 155

its upper end engaging in the slotted guide-ways, aforesaid, and means for sliding out

the foot of the brace and thereby erecting 160

the standard, substantially as described.

165

22. In a water-tower, the combination, with the running-gears and frame of a truck, of a 170

tower-supporting frame, a main standard having its base secured in said frame, and provided at its opposite end with slotted

guideways, a tower-brace supported in said frame and in sliding connection therewith, 175

its upper end engaging in the slotted guide-ways, aforesaid, and means for sliding out

the foot of the brace and thereby erecting 180

the standard, substantially as described.

185

23. In a water-tower, the combination, with the running-gears and frame of a truck, of a 190

tower-supporting frame, a main standard having its base secured in said frame, and provided at its opposite end with slotted

guideways, a tower-brace supported in said frame and in sliding connection therewith, 195

its upper end engaging in the slotted guide-ways, aforesaid, and means for sliding out

the foot of the brace and thereby erecting 200

the standard, substantially as described.

195

24. In a water-tower, the combination, with the running-gears and frame of a truck, of a 205

tower-supporting frame, a main standard having its base secured in said frame, and provided at its opposite end with slotted

guideways, a tower-brace supported in said frame and in sliding connection therewith, 210

its upper end engaging in the slotted guide-ways, aforesaid, and means for sliding out

the foot of the brace and thereby erecting 215

the standard, substantially as described.

205

25. In a water-tower, the combination, with the running-gears and frame of a truck, of a 220

tower-supporting frame, a main standard having its base secured in said frame, and provided at its opposite end with slotted

guideways, a tower-brace supported in said frame and in sliding connection therewith, 225

its upper end engaging in the slotted guide-ways, aforesaid, and means for sliding out

the foot of the brace and thereby erecting 230

the standard, substantially as described.

215

26. In a water-tower, the combination, with the running-gears and frame of a truck, of a 235

tower-supporting frame, a main standard having its base secured in said frame, and provided at its opposite end with slotted

guideways, a tower-brace supported in said frame and in sliding connection therewith, 240

its upper end engaging in the slotted guide-ways, aforesaid, and means for sliding out

the foot of the brace and thereby erecting 245

the standard, substantially as described.

220

27. In a water-tower, the combination, with the running-gears and frame of a truck, of a 245

tower-supporting frame, a main standard having its base secured in said frame, and provided at its opposite end with slotted

guideways, a tower-brace supported in said frame and in sliding connection therewith, 250

its upper end engaging in the slotted guide-ways, aforesaid, and means for sliding out

the foot of the brace and thereby erecting 255

the standard, substantially as described.

230

28. In a water-tower, the combination, with the running-gears and frame of a truck, of a 255

tower-supporting frame, a main standard having its base secured in said frame, and provided at its opposite end with slotted

guideways, a tower-brace supported in said frame and in sliding connection therewith, 260

its upper end engaging in the slotted guide-ways, aforesaid, and means for sliding out

the foot of the brace and thereby erecting 265

the standard, substantially as described.

235

29. In a water-tower, the combination, with the running-gears and frame of a truck, of a 265

tower-supporting frame, a main standard having its base secured in said frame, and provided at its opposite end with slotted

guideways, a tower-brace supported in said frame and in sliding connection therewith, 270

its upper end engaging in the slotted guide-ways, aforesaid, and means for sliding out

the foot of the brace and thereby erecting 275

the standard, substantially as described.

240

30. In a water-tower, the combination, with the running-gears and frame of a truck, of a 275

tower-supporting frame, a main standard having its base secured in said frame, and provided at its opposite end with slotted

guideways, a tower-brace supported in said frame and in sliding connection therewith, 280

its upper end engaging in the slotted guide-ways, aforesaid, and means for sliding out

the foot of the brace and thereby erecting 285

the standard, substantially as described.

245

31. In a water-tower, the combination, with the running-gears and frame of a truck, of a 285

tower-supporting frame, a main standard having its base secured in said frame, and provided at its opposite end with slotted

guideways, a tower-brace supported in said frame and in sliding connection therewith, 290

its upper end engaging in the slotted guide-ways, aforesaid, and means for sliding out

the foot of the brace and thereby erecting 295

the standard, substantially as described.

250

32. In a water-tower, the combination, with the running-gears and frame of a truck, of a 295

tower-supporting frame, a main standard having its base secured in said frame, and provided at its opposite end with slotted

guideways, a tower-brace supported in said frame and in sliding connection therewith, 300

its upper end engaging in the slotted guide-ways, aforesaid, and means for sliding out

the foot of the brace and thereby erecting 305

the standard, substantially as described.

255

33. In a water-tower, the combination, with the running-gears and frame of a truck, of a 305

tower-supporting frame, a main standard having its base secured in said frame, and provided at its opposite end with slotted

guideways, a tower-brace supported in said frame and in sliding connection therewith, 310

its upper end engaging in the slotted guide-ways, aforesaid, and means for sliding out

the foot of the brace and thereby erecting 315

the standard, substantially as described.

260

34. In a water-tower, the combination, with the running-gears and frame of a truck, of a 315

tower-supporting frame, a main standard having its base secured in said frame, and provided at its opposite end with slotted

guideways, a tower-brace supported in said frame and in sliding connection therewith, 320

its upper end engaging in the slotted guide-ways, aforesaid, and means for sliding out

the foot of the brace and thereby erecting 325

the standard, substantially as described.

265

35. In a water-tower, the combination, with the running-gears and frame of a truck, of a 325

tower-supporting frame, a main standard having its base secured in said frame, and provided at its opposite end with slotted

guideways, a tower-brace supported in said frame and in sliding connection therewith, 330

its upper end engaging in the slotted guide-ways, aforesaid, and means for sliding out

the foot of the brace and thereby erecting 335

the standard, substantially as described.

270

36. In a water-tower, the combination, with the running-gears and frame of a truck, of a 335

tower-supporting frame, a main standard having its base secured in said frame, and provided at its opposite end with slotted

guideways, a tower-brace supported in said frame and in sliding connection therewith, 340

its upper end engaging in the slotted guide-ways, aforesaid, and means for sliding out

the foot of the brace and thereby erecting 345

the standard, substantially as described.

275

37. In a water-tower, the combination, with the running-gears and frame of a truck, of a 345

tower-supporting frame, a main standard having its base secured in said frame, and provided at its opposite end with slotted

guideways, a tower-brace supported in said frame and in sliding connection therewith, 350

its upper end engaging in the slotted guide-ways, aforesaid, and means for sliding out

the foot of the brace and thereby erecting 355

the standard, substantially as described.

280

38. In a water-tower, the combination, with the running-gears and frame of a truck, of a 355

tower-supporting frame, a main standard having its base secured in said frame, and provided at its opposite end with slotted

guideways, a tower-brace supported in said frame and in sliding connection therewith, 360

its upper end engaging in the slotted guide-ways, aforesaid, and means for sliding out

the foot of the brace and thereby erecting 365

the standard, substantially as described.

285

39. In a water-tower, the combination, with the running-gears and frame of a truck, of a 365

tower-supporting frame, a main standard having its base secured in said frame, and provided at its opposite end with slotted

guideways, a tower-brace supported in said frame and in sliding connection therewith, 370

its upper end engaging in the slotted guide-ways, aforesaid, and means for sliding out

the foot of the brace and thereby erecting 375

the standard, substantially as described.

290

40. In a water-tower, the combination, with the running-gears and frame of a truck, of a 375

tower-supporting frame, a main standard having its base secured in said frame, and provided at its opposite end with slotted

guideways, a tower-brace supported in said frame and in sliding connection therewith, 380

its upper end engaging in the slotted guide-ways, aforesaid, and means for sliding out

the foot of the brace and thereby erecting 385

the standard, substantially as described.

295

41. In a water-tower, the combination, with the running-gears and frame of a truck, of a 385

tower-supporting frame, a main standard having its base secured in said frame, and provided at its opposite end with slotted

guideways, a tower-brace supported in said frame and in sliding connection therewith, 390

its upper end engaging in the slotted guide-ways, aforesaid, and means for sliding out

the foot of the brace and thereby erecting 395

the standard, substantially as described.

300

42. In a water-tower, the combination, with the running-gears and frame of a truck, of a 395

tower-supporting frame, a main standard having its base secured in said frame, and provided at its opposite end with slotted

guideways, a tower-brace supported in said frame and in sliding connection therewith, 400

its upper end engaging in the slotted guide-ways, aforesaid, and means for sliding out

the foot of the brace and thereby erecting 405

the standard, substantially as described.

305

43. In a water-tower, the combination, with the running-gears and frame of a truck, of a 405

tower-supporting frame, a main standard having its base secured in said frame, and provided at its opposite end with slotted

guideways, a tower-brace supported in said frame and in sliding connection therewith, 410

its upper end engaging in the slotted guide-ways, aforesaid, and means for sliding out

the foot of the brace and thereby erecting 415

the standard, substantially as described.

310

44. In a water-tower, the combination, with the running-gears and frame of a truck, of a 415

tower-supporting frame, a main standard having its base secured in said frame, and provided at its opposite end with slotted

guideways, a tower-brace supported in said frame and in sliding connection therewith, 420
